UNITED STATES PATENT OFFICE.

FRANCIS A. HOWARTH AND WILLIAM W. ARMOUR, OF WORCESTER, MASSACHUSETTS;
SAID ARMOUR ASSIGNOR TO SAID HOWARTH.

ALARM FOR AUTOMATIC SPRINKLERS.

1,263,416.

Specification of Letters Patent. Patented Apr. 23, 1918.

Application filed November 26, 1915. Serial No. 63,431.

To all whom it may concern:

Be it known that we, FRANCIS A. HOWARTH and WILLIAM W. ARMOUR, both citizens of the United States, residing at 5 Worcester, in the county of Worcester and Commonwealth of Massachusetts, have invented a new and useful Improvement in an Alarm for Automatic Sprinklers, of which the following is a specification, accompanied 10 by drawings forming a part of the same.

The object of our present invention is to provide an alarm adapted to be applied to an individual sprinkler head and to be operated directly by the action of the sprinkler head. We accomplish the above object, among others, by the construction and arrangement of parts as hereinafter described, the novel features being pointed out in the 15 appended claims.

20 Referring to the drawings,

Figure 1 represents a front elevation of a sprinkler head embodying our present invention.

Fig. 2 is a side view of the same shown in 25 longitudinal section.

Fig. 3 is a bottom view of the rotating distributor.

Fig. 4 is a vertical sectional view of the 30 strut through which pressure is applied to the cap for restraining the flow of water.

Figs. 5 and 6 are perspective views of the component parts of the strut.

Similar reference characters refer to similar parts in the different figures.

35 Referring to Fig. 1 of the drawings, 1 denotes a hollow screwthreaded nozzle adapted to be attached to a water supply pipe, and 2 is a hollow hub supported above the nozzle 1 by arms 3, 3. The nozzle 1 is 40 closed by a cap 4 which is held against water pressure in the supply pipe by means of a collapsible strut 5 having its lower end resting upon the cap 4 and adapted to receive at its upper end downward pressure exerted 45 by a screw 6 held in the hub 2. The strut 5 comprises in the present instance, two members 7 and 8 united by a locking bar 9, said locking bar being held in position by a bar of solder 10, fusible at a predetermined 50 temperature. The pressure is so applied to the cap 4 through the interposed strut 5 that the application of a predetermined degree of heat will melt the bar 10 and allow the strut to collapse, thereby releasing the

cap 4 by the pressure of water in the nozzle. 55 The construction of the strut herein shown and described forms no part of our present invention, as the same has been made the subject of a copending application filed by us November 29, 1915, Serial No. 64,163. 60

The lower end of the screw 6 carries a spindle 11 which bears against the upper end of the strut 5 and forms a pivot for a rotatable water distributor 12. The water distributor 12 is provided on its under side with 65 curved blades 13 against which the stream of water released from the nozzle 1 impinges with sufficient force to cause a rapid rotation of the water distributor 12. The outer periphery of the water distributor 12 is provided with a cam shaped projection 14 which is brought into forcible contact with the lower end 15 of a lever 16 pivoted at 17 upon a bracket 18 projecting from the side of the hub 2. The upper end of the lever 16 is 70 preferably provided with a hammer 19 in alignment with the rim of a bell 20 which is supported upon the upper end of the screw 6. The hammer 19 is normally held out of contact with the bell 20 by means of a blade 80 75 80 85

As soon as the flow of water occurs from the nozzle 1 by the release of the cap 4, due to the collapsing of the strut 5 the water distributor 12 is rapidly rotated by the pressure of the water which impinges against the curved blades 13. The rotation of the water distributor causes a rapid vibration of the lever 16 producing a violent ringing of the bell 20 which indicates that the individual 90 sprinkler head to which the bell is attached has been released by the action of the heat, thereby enabling the precise location of the fire to be determined. We are aware that alarm devices have been employed in connection with sprinkler systems, the operation of the alarm being determined by the duration of the flow of water through a 95 sprinkler head. We are also aware that it has been proposed to operate visible or audible alarms by the flow of water through a supply pipe leading to the sprinkler head. It has also been proposed to sound an alarm 100 in connection with the flow of water from the nozzle of an individual sprinkler head. 105 By our invention we provide extremely simple means which are entirely mechanical in their action and which depend upon the cir-

culation of water after it has been released, thereby obviating the use of electrical devices which are uncertain in their operation.

Our invention provides for the application of individual alarms to as many sprinkler heads in each room of a building as may be required in order to insure the operation of one or more alarms whenever sufficient heat exists to release a single 10 sprinkler head in the room.

We claim,

1. In an automatic sprinkler comprising a framework and a nozzle supported thereby, a member supported in the line of the 15 water discharge from said nozzle and rotatable thereby, a cam carried by said rotatable member, and a sound producing mechanism actuated by said cam.

2. In an automatic sprinkler comprising 20 a framework and a nozzle supported thereby, a member in the line of the water discharge from said nozzle and rotatable by the water discharge, a cam carried by said rotatable member, a lever pivoted upon the

framework, a spring for holding one end 25 of the lever in the path of said cam, a hammer carried by the opposite end of said lever, and a sound producing member in the path of said hammer.

3. In an automatic sprinkler, a framework 30 having a screwthreaded hub, a nozzle supported by the framework, a compression screw in said hub for closing said nozzle, a sound producing member mounted on said screw, a vibrating hammer mounted on said 35 hub, a member rotatable by the discharge from said nozzle, a cam carried by said rotatable member for actuating said hammer, and a spring for normally holding said hammer out of contact with said sound producing means.

Dated this 23rd day of November, 1915.

FRANCIS A. HOWARTH.
WILLIAM W. ARMOUR.
